COMBINED CHOPPING BLOCK AND BOWL

Robert R. Todd, 1743 SE. Locust, Portland, Oreg.

Filed Mar. 4, 1963, Ser. No. 73,796

Term of patent 14 years

(Cl. D44—1)

I claim:

The ornamental design for a combined chopping block and bowl, as shown.
